UNITED STATES PATENT OFFICE.

ALBERT BOND, OF NATICK, MASSACHUSETTS, ASSIGNOR OF ONE-HALF TO
JOHN W. CURRIER, OF NORTH TROY, VERMONT.

WRENCH.

SPECIFICATION forming part of Letters Patent No. 699,443, dated May 6, 1902.

Application filed March 1, 1901. Serial No. 49,439. (No model.)

To all whom it may concern:

Be it known that I, ALBERT BOND, a citizen of the United States, residing in Natick, in the county of Middlesex and State of Massachusetts, have invented an Improvement in Wrenches, of which the following description, in connection with the accompanying drawings, is a specification, like letters on the drawings representing like parts.

- 10 This invention relates to wrenches of that class known as "monkey-wrenches," and has for its object to provide a simple, efficient, and inexpensive wrench of the class referred to and one in which the usual threaded rod 15 and adjusting-nut are dispensed with. In accordance with this invention the shank to which the fixed jaw is attached has mounted on it a movable jaw provided with a beveled or tapering lug or projection, which is adapted 20 to be engaged by a sliding collar or yoke to lock the movable jaw in its adjusted position. These and other features of this invention will be pointed out in the claims at the end of this specification.
- 25 Figure 1 is a side elevation of a wrench embodying this invention. Fig. 2 is a front view of the wrench shown in Fig. 1 looking toward the right, and Fig. 3 a side elevation with the movable jaw disengaged from its 30 locking collar or yoke.

Referring to the drawings, *a* represents the fixed jaw; *b*, the shank provided with the removable handle *c*; *d*, the movable jaw which slides on the shank *b*, and *e* the locking collar or yoke for the movable jaw.

The movable jaw is made separate from the locking collar or yoke, but is adapted to be secured in its adjusted position by means of a beveled or tapering lug or projection *f*, extended from the bottom of said jaw, which is adapted to enter the upper portion of the yoke or collar between it and one side of the shank *b*, thereby rocking the said collar until the

shank is engaged by the upper edge of the back portion or bar of the collar and by the 45 lower edge of the front portion or bar of said collar. In practice the jaw *d* is moved toward the fixed jaw *a* until the nut to be turned is engaged by both jaws, and when in this position the locking-collar is moved along the 50 shank *b* and forced into engagement with the beveled lug or projection, thus locking the movable jaw in its adjusted position.

The parts of the wrench are plain and can be made and assembled at a minimum expense. 55 So, also, a finer adjustment may be obtained, as the movable jaw can be brought into close contact with the nut and held there while the locking-collar is engaged therewith.

I claim—

1. In a wrench of the class described, the combination with a fixed jaw and a shank to which it is secured, of a movable jaw mounted to slide on said shank intermediate the fixed jaw and the end of said shank, and a locking 65 collar or yoke mounted on said shank to move bodily thereon and adapted to engage said movable jaw, substantially as described.

2. In a wrench of the class described, the combination with a fixed jaw a shank to 70 which it is secured and a handle secured to said shank, of a movable jaw mounted to slide on said shank intermediate said fixed jaw and said handle, a beveled lug projecting from the under side of said movable jaw, and a locking-collar adapted to engage said lug to lock 75 the movable jaw in its adjusted position, substantially as described.

In testimony whereof I have signed my name to this specification in the presence of 80 two subscribing witnesses.

ALBERT BOND.
